UNITED STATES PATENT OFFICE.

HANS C. HANSON, OF STROUT, MINNESOTA.

BEST AVAILABLE COPY

GRAIN-SEPARATOR.

SPECIFICATION forming part of Letters Patent No. 885,213, dated January 1, 1901.

Application filed June 6, 1900. Serial No. 19,238. (No model.)

To all whom it may concern:

Be it known that I, HANS C. HANSON, a citizen of the United States, residing at Strout, in the county of Meeker and State of Minnesota, have invented certain new and useful Improvements in Grain-Separators; and I do declare the following to be a full, clear, and exact description of the invention, such as will enable others skilled in the art to which it appertains to make and use the same.

This invention relates to grain-separators, and particularly to the class employing shaking screens and an air-blast fan.

The object is to provide a device of this character which is simple in construction, efficient in its work, and easily operated, and which may be conveniently moved from place to place.

With this and other objects in view my invention consists in the combination and arrangement of parts, as will be hereinafter described and claimed.

In the accompanying drawings, in which like characters of reference indicate like parts, Figure 1 is a side elevation of my improved grain-separator. Fig. 2 is a similar view of the opposite side. Fig. 3 is a longitudinal vertical section through the center of the machine, and Fig. 4 is a horizontal sectional view on the line of the fan-shaft.

The supporting-framework of my device preferably consists of two X-shaped supporting-standards, each formed of the inclined or oblique bars 2, 3 and 2^a, 3^a, mortised together near their upper ends to form the X-shaped supporting-standards, each pair of bars 2, 3 and 2^a, 3^a being connected together near their lower ends by the parallel longitudinal side rails 4, which are formed on their extended ends with hand-grips for conveniently moving the machine. These supporting-standards are suitably spaced apart and held by the cross-braces or tie-rods 5.

Between the upper portions of the X-shaped supporting-standards is mounted the grain-hopper, formed by the parallel side pieces 6 and the inclined front and rear walls 7 and 8, respectively, the side pieces 6 also being provided with the downwardly and inwardly converging deflector-blocks 6^a to conduct the grain to the square feed-delivery roll, to be hereinafter described.

Immediately below the grain-hopper and to the rear of the same is rigidly mounted the fan-casing 9, in which is inclosed the usual blast-fan, the shaft 9^a of said fan being journaled in bearings in the oblique bars 2 and 2^a and being provided on one end with a fly-wheel 10 and on the opposite end with the belt-pulley 12. The shaft 9^a is provided near both ends and within the fan-casing with cranks, to which are attached pitman-rods 13, the forward ends of which are connected to a movable framework 14, carrying the screens.

The framework 14 consists of the upper and lower parallel side pieces 15, 16, connected at their forward ends, the lower pieces 16 inclining downwardly and rearwardly and being much longer than the upper pieces 15. The said parallel sides 15 and 16 are spaced 70 apart and held by suitable braces and tie-rods.

The parts just described form the shaking frame 14, which is actuated by the aforesaid cranked fan-shaft and pitmen and is suspended at its upper end from the forward extensions of the parallel side pieces 6 of the hopper by means of the pivoted straps or links 14^a, and at its lower rear end from the side rails of the supporting-framework by similar straps 14^b, thus allowing said frame 14 to be reciprocated backwardly and forwardly.

In the upper portion of the frame 14, between the parallel side pieces 15, is mounted a coarse screen A, which receives the grain 85 from the hopper through the medium of a square feed-roll 17, journaled immediately below the mouth of the hopper, one end of the shaft of said feed-roll being extended and provided with a belt-pulley 17^a. Below this screen 90 are two other screens A^a and A^b, arranged one immediately below the other, the screen A^a being of a finer mesh than the screen A, but of coarser mesh than the screen A^b. A grain-board A^c is located below this graded 95 set of screens A, A^a, and A^b and serves to receive the grain falling therefrom and conduct it to the lower sets of screens, hereinafter described. The square feed-roll 17 has two of its opposite sides concaved their entire length, 100 forming pockets which receive the grain from the hopper and deliver it to the screen A.

In the lower portion of the frame 14 and between the parallel side pieces 16 is mounted

the screen B, which extends the entire length of said side pieces and is provided with a series of depressions or steps, as shown, which causes the grain to move over said screen slowly, thus thoroughly eliminating the small and inferior grains and allowing the first-class grain to pass to the end of the screen and onto the delivery-spout 18, which is pivoted on the lower tie-rod 5^a of the frame 14.

10 A coiled spring 20 is provided beneath the frame 14, having one end attached to a tie-rod 5^b in the supporting-standards and the other end attached to the shaking frame 14, the force of the spring being exerted to give 15 the movable parts a quick jerky motion.

Interposed between the upper graded set of screens A, A', and A² and the screen B at the front of the frame is an oat-cleaner consisting of a perforated plate or screen D, having 20 openings which are somewhat smaller than the openings in the upper set of screens A, A', and A². The grain is conducted to the forward and highest end of the screen D from the grain-board A³ by a curved plate 21, connected to the forward ends of the upper and lower side pieces 15 and 16 of the shaking frame 14 and serving as a shield to prevent the grain falling from the front end of the grain-board from passing out at the front 25 of the machine. Located at the lower end of the screen D is an inclined delivery-chute 22, which is arranged to conduct the oats laterally to one side of the machine, where they may be received in a suitable receptacle, and located at the upper end of said screen D is a transverse roll 23, removably secured to the side pieces 16 of the frame 14, so as to be readily applied to and removed from the shaking frame. One end of the apron is attached to the roll, while the opposite end 30 thereof is free and unconfined. By this construction the apron may be conveniently wound upon the roll whenever it is desired to expose the screen D and whenever it is desired to remove the oat-cleaning device from 35 the shaking frame.

In the practical operation of the machine the grain is fed from the hopper onto the screen A through the medium of the feed-roll 17, and thence passes downwardly through 40 the screens A' and A² and onto the grain-board A³, the "white caps" and the pieces of straw and such other refuse matter as the grain may contain being blown out at the front of the machine. The grain then falls 45 from the feed-board down onto the front upper end of the screen B, being guided thereto by the curved shield-plate 21. The vibratory motion of the shaking frame 14 then causes

the grain to move rearwardly down the inclined screen D and under the flexible apron 5^a 50, which serves to yieldingly retain the grain in contact with said screen and cause the wheat to be separated from the oats and forced through the openings in the screen D down onto screen B therebelow. The openings in the screen D are somewhat smaller than the openings in the upper set of screens A, A', and A², so as to prevent the passage of oats therefrom and down onto screen B, so that the oats are forced to pass downwardly 55 along the upper surface of the screen D and are thereby conducted into the chute 22, from which they discharge at the side of the machine. The grains of wheat thence pass along the surface of the screen B, the first-class 60 grain passing into the delivery-spout 18, while the inferior grains fall through and onto the screen C. The grain discharges from the screen C onto the floor or into a suitable receptacle at the rear of the separator under 65 the spout 18, the grain passing beneath said spout and dropping from the rear end of said screen.

As shown in the drawings, the parts of the device are arranged in position for separating 70 oats, straw, and other foreign matter from wheat. To adapt the device for separating wheat and other smaller grains from oats, it is simply necessary to substitute for the upper set of screens A, A', and A² a coarse-wire 75 screen and to remove the oat-cleaner, leaving the two lower screens B and C in position, as for wheat.

Various changes in the form, proportion, and minor details of construction may be resorted to without departing from the principles or sacrificing any of the advantages of 80 this invention.

Having thus described my invention, what I claim, and desire to secure by Letters Patent, is—

In a grain-separator, the combination, with a frame and a shaking shoe mounted therein, of an oat-cleaning device mounted on said shoe and comprising a screen, a roll detachably mounted in the frame at the head of the screen, and a flexible apron covering the screen and secured at one end to said roll, the opposite end of the apron being free and unconfined so that the apron may be wound 90 upon the roll so as to expose the screen and adapt the roll and apron for removal from the frame, substantially as set forth.

In testimony whereof I have hereunto set my hand in the presence of two subscribing 95 witnesses.

HANS C. HANSON.
